United States Patent

Des. 240,700
Patented July 27, 1976

240,700

COMBINED ELECTRIC CAN OPENER AND CUTLERY GRINDER

Robert J. Scott, Blue Springs, and Bill G. Mead, Raytown, Mo., assignors to Rival Manufacturing Company, Kansas City, Mo.

Filed Mar. 20, 1975, Ser. No. 560,298

Term of patent 14 years

Int. Cl. D7—99

U.S. Cl. D8—35

Fig. 1.

Fig. 3.

Fig. 4.

Fig. 2.

Fig. 5.

Fig. 6.

Fig. 8.

FIG. 1 is a perspective view showing the front and left side views of the combined electric can opener and cutlery grinder;

FIG. 2 is a front elevational view thereof;

FIG. 3 is a top plan view thereof;

FIG. 4 is a bottom plan view thereof;

FIG. 5 is a rear elevational view thereof;

FIG. 6 is a right side elevational view of FIG. 2;

FIG. 7 is a left side elevational view of FIG. 2; and

FIG. 8 is a perspective view similar to FIG. 1, but showing the rear and opposite side of same.

We claim:

The ornamental design for a combined electric can opener and cutlery grinder, as shown and described.

Fig. 7.
